UNITED STATES PATENT OFFICE.

CLIFTON CHISHOLM, OF CLEVELAND, OHIO, ASSIGNOR TO AMERICAN MULTIGRAPH COMPANY, OF CLEVELAND, OHIO, A CORPORATION OF OHIO.

METHOD OF LOCKING PRINTING STRIPS IN PLACE.

Application filed August 14, 1925. Serial No. 50,155.

I have devised a system of printing wherein embossed strips are removably mounted on a suitable holder, as for instance on an address plate or a flexible 5 blanket adapted for mounting on a rotary drum. Such plate or blanket has rows of projections or raised buttons which the embossed strips overlie, and on which they are retained by inwardly turned edge flanges on 10 the strips extending beneath overhanging portions of the buttons. This provides a very simple portable printing form.

It is desirable, however, that means be provided to prevent the strip shifting longitudinally on the holder. I have discovered that such movement may be readily prevented by giving its opposite edges a slight inward distortion, causing them to bind against the buttons or projections of the 20 holder, and furthermore that such inward distortion may be entirely effective to prevent shifting without in any manner distorting the printing surface of the strip. My invention is concerned with this method 25 of locking the printing strip in place.

The drawings serve to illustrate the method. Fig. 1 is a cross-section through a rotary printing machine having a button-blanket carrying embossed printing strips 30 and illustrating the application of a tool for indenting the edges; Fig. 2 is a development of a portion of the surface of such printing device equipped with a flexible blanket and printing strips; Fig. 3 is a perspective 35 of a portion of a holder or blanket, a strip thereon and a device for indenting the edges of the strip; Figs. 4 and 5 are enlarged cross-sections through strips and their blanket illustrating the position of the 40 strip before the indenting action takes place and after it is completed respectively; Fig. 6 is a perspective of one of the strips after its edges have been indented,—the amount of indentation being exaggerated for clear- 45 ness of illustration.

As illustrated in Fig. 1, 10 indicates a segment of a drum mounted on a rotary driving shaft 11 and adapted to carry a flexible sheet metal blanket 20 on which are mounted 50 embossed printing strips 30, which when the drum rotates may cooperate with a suitable roller platen 15 to print—ink being supplied by any suitable means, not shown.

The blanket 20 is constructed in accordance with Patents Nos. 1,438,584 and 1,438,

582 granted to The American Multigraph Company December 12, 1922, on applications of William J. Demming and Burnie J. Craig respectively. As clearly shown in Figs. 2 and 3, this blanket has rows of up-standing buttons 21 connected in the direction of the row by upstanding corrugations 22. The tops of the corrugations and the tops of the buttons come to the same plane along the central zone of the buttons, but the arcuate edges of the buttons extend beyond the corrugations in each direction and overhang the body of the plate some distance above its main region, as illustrated in Figs. 3, 4, and 5. Thus the buttons and intermediate corrugations form a continuous support for the embossed strips 30.

The edges 31 of the embossed strips are curled inwardly beneath the buttons to underhang them so that such strips may be slid endwise into place on the holder and thereafter will be retained against outward or radial movement. The strips may lie close to each other as shown in Fig. 2.

The problem presented is to lock the strips 80 against longitudinal displacement of the holder, after they have been put in position. I have discovered that by inwardly indenting the opposite edges of the strip a slight amount, and for a distance at least as great 85 as from one button to the corresponding portion of the adjacent button, the strip may be firmly locked in place. The strips are preferably made of comparatively soft material, as aluminum, for instance, and a slight 90 edge indentation suffices to force the metal against the edges of the adjacent button or buttons. The degree of the indentation has been exaggerated in Figs. 2 and 6 for proposed clearness of illustration, but a comparison of Figs. 4 and 5 illustrates the comparatively slight degree of distortion necessary to be effective.

The distortion may be accomplished by 100 means of a suitable block placed against the edge of the strip and the delivery of a comparatively light blow to this block. Such block preferably has inclined separated jaws engaging opposite edges of the strip so that 105 an inward blow is delivered to both edges at the same time by a blow on the block directed normally to the course of the holder. It is important that the indentation be at least as long as the distance from one button on the holder to the correspond-

ing portion of the next button, so that the strip will not be forced inwardly between the buttons, which would distort the printing surface, but simply against the edges of one or more buttons. A block having such length of jaw may be placed at any point on the strip, since it is immaterial whether it forces the strip simply against the opposite edges of one button, or against the edges of two adjacent buttons.

It is important that the blow which indents the edges be not excessive, otherwise the strip will be distorted in its printing region. Accordingly, means are preferably provided for delivering a blow of constant force. I find that it is desirable to provide the hammer block with a flat surface which engages the face of the character as the block comes to its final position, thus flattening such face if the blow has bowed the strip upwardly to any extent.

A suitable implement for engaging the edges of the strip is illustrated in the drawing at 40. This implement has spaced inwardly beveled jaws 41 adapted to engage the opposite edges of the strip as illustrated in Figs. 4 and 5. 42 in Fig. 1 discloses a handle for the implement which may receive a blow extraneously delivered, though I prefer to employ an internal spring 43 and a hammer 44 which is automatically released when the spring is compressed to deliver a constant blow to the hammer block 40.

An internal mechanism for effecting a constant blow is illustrated in my application No. 739,946 filed September 25, 1924, of which the present application is a continuation in part. The implement described is advantageous in that it may be simply placed against the strip and the handle forced inwardly manually and blows of constant force delivered by means of an internal spring and hammer, and excessive blows avoided.

Whether the blow is delivered by an internal spring or by external means impinging the handle, they may be applied after the strips are mounted on the holder, and as shown in Fig. 1, may be radially delivered after the holder with the strips is mounted on an arcuate frame on a printing drum.

My invention provides a very simple and effective means for locking the strips against longitudinal shifting on their holder and is equally applicable whether the strips be mounted close together, as for printing single space, or whether they are mounted some distance apart. The width and depth of the groove in the block between the jaws 41 is sufficient to clear the embossed characters on the strip when the tool is first applied, the bottom of the groove being preferably flat a suitable distance above the characters as illustrated in Fig. 4. The depth of this groove bears such relation to

the angular inclination, that when the proper amount of indentation to the edges of the strip has been made, the base of the groove impinges the face of the characters beneath it and thus immediately restores this face to a flat plane, if the indentation of the edges distorted it. If the internal spring arrangement of tool shown in Fig. 1 is employed, it is to be understood that the spring has force enough to cause the hammer block to take the position shown in Fig. 5.

Having thus described my invention, I claim:

1. The method of binding a flanged printing strip on a holder having a row of raised projections which the strip overlies, comprising indenting the edge of the strip for a distance at least as great as that from one projection to the corresponding portion of the adjacent projection.

2. The method of binding a flanged printing strip on a holder having a row of raised projections which the strip overlies and beneath the edges of which its flanges extend comprising indenting opposite edges of the strip for a distance at least as great as that from one projection to the corresponding portion of the adjacent projection.

3. The method of binding a flanged printing strip on a holder, having a row of raised buttons which the strip overlies and beneath the edges of which its flanges extend comprising simultaneously indenting the opposite edges of the strip for a distance at least as great as that from one button to the corresponding portion of the adjacent button by the delivery to the strip of a blow of definite amount.

4. The method of binding flanged printing strips on a holder having rows of raised projections which the strips overlie and beneath the edges of which its flanges extend, comprising indenting the opposite edges of the strip simultaneously for a distance at least as great as that from one projection to the corresponding portion of the adjacent projection by means of a blow delivered in a direction normal to the surface of the strip on members which lie in an inclined direction in engagement with opposite edges of the strip.

5. The method of binding flanged printing strips on a holder having rows of raised projections which the strips overlie and beneath the edges of which their flanges extend comprising simultaneously indenting by a single blow, the opposite edges of a strip for a distance at least as great as that from one projection to the corresponding portion of the adjacent projection, and repeating this operation for different strips, the forces of the blows on the different strips being the same.

6. The method of binding a printing strip on a holder having a raised projection which

the strip overlies, comprising simultaneously indenting the opposite edges of the strip while it is mounted on the holder and as the indentation is being completed flattening 5 any upwardly bowed character between the indentations.

7. The method of binding a flanged printing strip on a holder having a row of raised projections which the strip overlies and beneath the edges of which its flanges extend 10 comprising indenting opposite edges of the strip for a distance at least as great as that from one projection to the corresponding portion of the adjacent projection and at 15 the completion of the indentation pressing a plane surface against the face of the characters.

8. The method of binding a printing strip on a holder having a row of spaced raised 20 projections which the strip overlies, comprising indenting the edge of the strip for a distance less than its length while it is mounted on the holder in a manner to insure a projection being engaged by an indentation.

9. The method of binding a flanged sheet metal printing strip on a holder having a row of raised projections on which the strip rests and beneath which its flanges project, 30 comprising indenting the flange in a manner which will insure the engagement of a projection by an indentation, though the in-

denting tool may be variably positioned with reference to the strip.

10. The method of binding a flanged sheet 35 metal printing strip on a holder having a row of raised projections on which the strip rests and beneath which its flanges project, comprising indenting both flanges for a distance less than the length of the strip and in 40 a manner which will insure the engagement of the opposite edges of the same projection.

11. The method of binding a flanged printing strip on a holder having a raised projection which the strip overlies, comprising 45 indenting the edge of the strip for a distance materially less than the length of the flange while it is mounted on the holder and while using the holder as an anvil to cause the strip to bind against the edge of 50 the projection.

12. The method of binding parallel adjacent printing strips on a holder having rows of raised projections which the strips overlie, comprising 55 indenting the opposite edges of previously formed flanges of different strips in isolated regions to bring such regions farther in than the most of the flange, while the strips are mounted on the holder to cause them to bind against the edges of the raised 60 projections.

In testimony whereof, I hereunto affix my signature.

CLIFTON CHISHOLM.
